DESIGN FOR A BUTTON

Arthur F. Donovan, West Hartford, Conn., assignor to Colt's Patent Fire Arms Manufacturing Co., Hartford, Conn., a corporation of Connecticut

Application October 5, 1937, Serial No. 71,981

Term of patent 7 years

To all whom it may concern:

Be it known that I, Arthur F. Donovan, a citizen of the United States, residing at West Hartford, in the county of Hartford and State of Connecticut, have invented a new, original, and ornamental Design for a Button, of which the following is a specification, reference being had to the accompanying drawing, forming part thereof.

On the drawing:

Fig. 1 is a front view of a button embodying my new design.

Fig. 2 is an edge view thereof.

Fig. 3 is a sectional view along the line 3—3 of Fig. 1.

The dominant feature of the design comprises in part the general contour as shown and comprises in part the surface ornamentation as shown, the said contour including the approximately hemispherical front surface joined by an annular surface of small radius to an approximately flat rear surface, and the said surface ornamentation being confined to the said approximately hemispherical front surface and consisting of small circular depressions arranged in rows approximately at right angles to each other.

I claim:

The ornamental design for a button as shown and described.

ARTHUR F. DONOVAN.
